ENVELOPE MACHINE

Abraham Novick, Flushing, N. Y., assignor to F. L. Smith Machine Co., Inc., New York, N. Y., a corporation of New York

Application April 17, 1940, Serial No. 330,006

25 Claims. (Cl. 93—62)

This invention relates to machines for fabricating envelopes and the like, such as envelope folding apparatus, and particularly to feeding and forwarding mechanism suitable for use in such apparatus, and this application is a continuation in part of application Ser. No. 67,243, filed March 5, 1936, for Envelope machines.

In this type of machine the blanks are discharged from certain types of unit, such as gummers and driers, in fanned out overlapping relation with the trailing end of each blank overlying the advance end of the preceding blank. For succeeding operations, however, it is necessary to separate the blanks and feed them individually to folding or other units. In carrying out this operation, involving the change from an overlapping stream of blanks to an individualized series thereof, it is important that the blanks be accurately aligned for the succeeding operation, and that the change be carried out with a minimum of delay and in minimum space.

A principal purpose of this invention is to provide a construction for carrying out this operation. In general, this is accomplished by bringing the leading edges of the overlapped blanks into contact with stop means which will assure alignment, and then transferring the aligned blanks individually to a conveying means which will feed them appropriately to the succeeding unit.

A feature of the invention is the employment of transferring means for the purpose indicated which will engage the upper surface of the uppermost blank resting against the stop, lifting the blank and shifting it into position for engagement by the succeeding conveyor. With this construction the travel of underlying blanks into engagement with the stop is not interfered with, and the transfer is effective even if a number of blanks should accumulate against the stop.

The invention is advantageously applicable to an arrangement in which the blanks are transferred from their position against the stop in a direction transverse to their direction of travel to the stop. In this arrangement the second conveyor means extends to the side of the first conveyor means adjacent the stop, in position to receive a side margin of the uppermost blank when shifted appropriately by the lifting means.

This arrangement is particularly appropriate in envelope machines of known types in which the envelope blank, after passing through one unit with a certain margin in advance, must be fed to the succeeding unit with an adjacent or lateral margin in advance. This is best accom-

plished by transferring the envelopes sidewise from the first conveyor to the second conveyor. For instance, after the envelope blanks have been folded with the exception of the seal flaps, which have been gummed and dried, the blanks must go into a right-angle run for the purpose of closing the gummed flaps seriatim. In this and similar arrangements it is important that the blanks be carefully aligned when fed to the second conveyor for such folding.

Heretofore, it has been possible to fold the seal flap after the drying operation only by first separating the envelopes from overlapping relationship to individualize each envelope with its seal flap open, and then make the right-angle turn of each envelope. In some machines, the overlapped blanks are individualized by means of segmental devices and then the right-hand turn is made at high speed to permit the individualized blank so turned to be cleared from the path of succeeding blanks as they approach the individualizing segment.

In no instance has it been made possible to take the envelope blanks directly from the aforementioned overlapping band formation into a right-angle run for folding, so that the above machines operated under the disadvantage that it was necessary to go through the step of individualizing the envelopes, the separating mechanism being arranged to operate on the envelopes while they are in the overlapping relationship.

Owing to the fact that the envelopes are generally longer than they are wide, and are fed from the drier in the direction of their major axis, the sidewise speed of transfer can be slower than a corresponding speed has to be when the envelopes are separated lengthwise for individualization prior to the right-angle turn.

An incidental advantage of the sidewise transfer according to the present invention is that the envelope being transferred is lifted more slowly, so that the envelope that comes underneath into place against the stops is not dragged sidewise also.

Another object of the invention is to provide a sucker or analogous form of transfer device by means of which the envelope being transferred is picked up by the corner nearest the stop, this corner being nearest the direction in which the envelope is to be transferred. By this placement of the sucker the envelope is advanced in its aligned condition and the accuracy of alignment

is maintained while the transfer is taking place. By the above arrangement the feeding of doubles is avoided, this being of frequent occurrence when other transfer devices are employed, such as segmental rollers.

Under such conditions, an object of the present invention is to make the preliminary individualizing step unnecessary by operating on the leading envelope of the band as each arrives at suitable stops, the mechanism taking each in turn as it arrives and moving it sidewise so that it becomes separated from the others and continues in a direction parallel to the stops so that the flap may be folded by conventional folding mechanism.

A further object is to "square" each envelope while it is moving at the slow overlapped speed ¹⁰ to the stop, thus eliminating any tendency to bounce or rebound from the stop, and therefore giving a more dependable alignment by reason of the slow speed at which this aligning step is performed.

A further object is to provide for removing from the aligned position at a higher speed the envelope which has thus been accurately aligned at the relatively lower speed of the overlapping band relationship.

A further object of the invention is to effect such a disposition of the mechanisms that they are individually easy of access and easy to inspect while in operation.

Other features and advantages of the invention will appear as the description of the particular physical embodiment selected to illustrate the invention progresses.

Drawings are appended, in the several views of which like characters of reference have been applied to corresponding parts throughout the drawings, wherein:

Fig. 1 is an elevational view of somewhat schematic character illustrating the elements used in carrying out the early stages of the operation for which provision is made by the present invention;

Fig. 2 is a similar view of other elements used in carrying out stages of the operation subsequent to those of Fig. 1, and illustrates a run of mechanism which in practice is disposed at an angle to that of the run shown in Fig. 1;

Fig. 3 is a view, on an enlarged scale, showing in detail the right-hand portions of the mechanism illustrated in Fig. 1;

Fig. 4 is a detail view in vertical section on the line 4—4 of Fig. 3;

Fig. 5 is a detail view in horizontal section on the line 5—5 of Fig. 4;

Fig. 6 is a schematic side elevation of a straight line transfer construction; and

Fig. 7 is a schematic plan view of part of the construction shown in Fig. 6.

In a preferred form of the invention selected for illustration and description and shown in Figs. 1-5, the part designated generally by the reference character F is the frame of an envelope making machine adapted to receive from a suitable source of supply, as for example from the drier conveyor mechanism M', at the left of Fig. 1, a continuous supply E of envelope blanks arranged to travel in overlapping, fanned out relation to each other, the darker lines 10 in Fig. 1 indicating in diagrammatic fashion the end flaps of the blanks which have preferably been gummed at an earlier stage and are shown as trailing as the line advances from left to right,

the gummed face of each flap being turned upwardly.

The general shape of the envelope E being fabricated is indicated in Fig. 5 by dash-dot lines, this envelope being of a known open-end type, having a pasted overlap seam 12 along its major axis, and having an end flap 13 at its leading end, the envelope blank arriving (with the aforesaid seam and end flap pre-sealed) for further treatment by the mechanism herein disclosed.

Such treatment may comprise the folding over of the flaps 14, as herein illustrated and the eventual delivery of the completed envelopes, at the end of the run designated R'' in Fig. 2, to a mechanism for restacking them, the reference character M'' in Fig. 2 designating a portion of the last-named mechanism, for a further disclosure of which recourse may be had to my Patent No. 2,140,112, issued December 13, 1938.

Reverting to the run of mechanism shown schematically at R, R' in Fig. 1, the blanks E are fed thereto from the conveyor C of mechanism M', bridging the gap to a conveyor belt 14 which runs on an idler 15, a driving pulley 16 and idlers 17, 18 in the order named, the stretch 19 of belt 14, between idler 15 and driving pulley 16, being inclined so that when delivered by the belt 14, the blanks are at a suitable height to bridge gap G and pass on to the conveyor belt 21 of run R', the latter running upon rolls 22, 23 journaled upon the frame F at about the elevation indicated in Fig. 1.

During advancement along the run R the overlapping blanks move under a hold-down bar 24, and are influenced by rollers 25, 26, 27, 28, 29 and 30, which bias the blanks against the advancing stretch 19 of the underlying conveyor belt. Roller 31 cooperates with the conveyor 21 to feed the blanks, said conveyor running at a speed in excess of the linear speed of the belt 19, so that the blanks are fanned out more and more as they travel along this stretch 21 of the belt conveyor of run R' and under an idler roll 32 which presses the blanks against the belt 21.

This roll holds the trailing end 10' of the contiguous blank 10 while its leading end 20 is drawn forward by the belt 21 until the leading end engages the stops 33 and 33x, each blank being thus pulled by conveyor 21 into its appropriate intended position below one or more preceding blanks, the uppermost blank E' of the pile P, Fig. 1, being free for transfer to the run R'' as will be duly described.

This pile is intended to be temporary in character, serving as a clearance pile, and desirably comprises not more than a few blanks at any given time, so that the weight of superimposed blanks may only be sufficient to serve as a biasing means (in the absence of any pressing down roller), to maintain a good frictional contact between the mutually contiguous faces of the belt 21 and the ends 20 of envelopes that are being advanced to the stops 33 and 33x.

This insures accurate registration of the forward ends of the superimposed blanks with each other (E', E'', Fig. 1) and accurate positioning of each blank for subsequent transfer operations with respect to seal flap folding mechanism hereinafter described; and it is to be noted that at this critical stage the blanks are exposed seriatim to the inspection of the operator, so that a defective blank can readily be "spotted" and removed without stoppage of the machine or interference in any way with its rapid operation.

In pursuance of an important object of the

invention, the transfer from run R' to run R'' of each topmost blank E' of the clearance stack or pile is accomplished by the provision of a transfer member T to which is imparted an intermittent feeding action causing it to perform a recurrent cycle of movements. These include first a depression of the transfer member T, which in this instance takes the form of a sucker arm connected by tube 38 (Fig. 5) with a suitable source of suction (not shown), into sucking contact with the top blank E' of pile P, the sucker engaging the upper right-hand corner of the partly formed envelope E' (Fig. 5); then ensues an upward shift of the sucker arm T which picks up the top blank E' and subsequently pushes it in a horizontal direction into the bite of conveyor belts 36, 37, the sucker arm being then retracted for performance of another similar cycle of transfer operations, by mechanism to be described.

In passing, however, it should be noted, first, that the belts 36, 37 operate at a level above that of the clearance pile P and at an angle to the direction of feed of the blanks to pile P, at right-angles in the instance illustrated. The angle between the run R'' and the runs R, R' may, of course, be designed for suitable disposition of their supporting and actuating means, and will be governed by considerations of economy in space and power as well as convenience in operation and inspection.

It is also to be noted that the arm T propels the blank E' in such a direction, parallel to the stops 33, 33x, that the blank is caused by inertia, and by frictional contact of its trailing portion 11 with the underlying table 120, to swing about the point of engagement by the sucker, and thus the blank maintains its contact with the stops and is guided thereby in correct alignment with the direction of the run R''.

In the instant illustrative embodiment the conveyor belts 36 and 37 run over rolls 38 and 39, thence between a pair of pressure guide rolls 40 designed to regulate the bite of the belts upon the blanks E; then each blank is carried along separately, with its end flap 11 free of the belts, which run between a multiplicity of pairs of rolls 41, 42, the roll 41 of each pair being that beneath the belts and extending from one side to the other of the frame F (Fig. 5). The rolls 42 are disposed above the belts and are quite narrow.

In the embodiment illustrated in Figs. 6 and 7 the same general principles of operation, with the envelopes aligned at the stop for transfer to a succeeding conveyor construction, are utilized; but the two conveyors are in alignment. The uppermost envelope lifted by the sucker means is picked up by a segment operating against a presser roll shifted beneath the envelope blank, feeding the blank into the bite of the succeeding conveyor. This construction likewise serves to align the envelopes against the stop, and permits the travel of succeeding envelope blanks into engagement with the stop beneath the uppermost blank while the latter is lifted and shifted to the second conveyor.

The foregoing description sets forth somewhat summarily the elements of a machine embodying the invention in their cooperative combination.

The structural details of the particular physical embodiment selected for illustration will now be described with especial reference to Figs. 3, 4 and 5, in which the mechanism of the run

designated R'' in Fig. 2 constitutes the principal subject matter, enough of the runs R and R' being shown to aid in understanding the relationship of the parts.

Beginning then at the left hand side of Fig. 3, the driving pulley 16 for conveyor belt 14 of run R is mounted on a shaft 43 journaled in brackets 44 and 44x extending from a side member 45 of the frame F, suitable cross-members 46, 47 and a base, not shown, connecting this side member 45 with a similar side member 49 across the width of the frame.

A gear 50 on shaft 43 meshes with a carrier gear 51 upon a stud shaft 52, fixed in an arm 53 of the bracket 44 (Figs. 4 and 5) and gear 51 meshes with pinion 54 secured to a shaft 55 and having secured thereto a gear 56 meshing with an intermediate changeable gear 57 on stud 58 which is driven by a gear 60, this stud being mounted in either of two orifices 59 and 59a, by which changes of speed of the belt 14 may be effected to change the spacing between the envelopes. For example, if the stud 58 is inserted in the aperture 59a and a gear 57 of larger diameter is substituted, arranged to mesh with the gear 60 and the pinion 54 (which is smaller in diameter than gear 56), the spacing between the envelopes is decreased. The gear 57 is shown as meshing with the pinion 60 on a spline shaft 61 upon which is fitted for axial adjustment a bevel gear 62, the latter being supported in a bracket 64x of a carriage 64.

Associated with bevel gear 62 is a complementary bevel gear 63 fixed to shaft 67, the latter being supported at its opposite ends in side plates 64Y of the carriage 64 and serving to actuate the pulleys 38 and the conveyor belts 36 which run thereto over idlers 68, 69, 70, after passing over the bed pulleys 41. The pulleys 70 all run on a shaft 71 fitted within the frame in appropriate position, and the belts 36 can be kept taut by adjustment of a pair of arms 73 held by bolts 73x on cross bars 74 secured at their ends to the plates 64Y of the carriage 64.

The complementary conveyor belts 37 run to rolls 39 from a long idler roll 75 (Figs. 3 and 4) and idler rolls 76 and 76x, the long roll having a shaft 77 journaled in brackets 78 of carriage 64 and the idlers 76, 76x being adjustable laterally of the machine, as by suitable mounting in brackets 79 set by screws 80 on the cross-rod 46. In the form illustrated, said rolls 76, 76x are journaled on stud-bolts 81 set in slots 82 in the arms 83 of the brackets 79. Shaft 84 which drives conveyor rolls 39 is journaled at each end in a swinging bracket 85 mounted pivotally, as at 86, upon one of the upright brackets 78 (Fig. 4). This shaft has a gear 87 meshing with a gear 88 on shaft 67 by which the conveyor belt pulleys 38 are driven at suitable speed to cause equal linear speed of the conveyor belts 36 and 37.

Feed sectors 84X (Figs. 4 and 5) are secured to the shaft 84 and cooperate with the belts 36 to grip the edge of the envelope after it has been inserted between the belts 36 and 37 by the transfer member T.

The swinging brackets 85 have arms 89 (Fig. 4) between the free ends of which and the brackets 78 are coil springs 90 mounted upon bolts 91 and maintained under compression, so that the shaft 84, rolls 39 and the sectors 84x are biased yielding toward the rolls 38. The nuts 92 limiting the biasing movement in order to maintain the belts 36, 37 with a tapering "bite" as shown clearly in Fig. 2.

The springs 90 permit yielding movement of the segments and insure pressure of the latter against the belts 36 irrespective of the thickness of the material used.

The entire system of mechanism heretofore described derives its actuation through gears 93, 94 from main driving shaft 95, journaled in side members 64X of carriage 64 and driven through the medium of a chain and sprocket (not shown) by a source of power suitably coordinated with the other mechanisms, but not shown. A pinion shaft 98, with hand wheel H, serves to permit manual shifting of the carriage 64 through the rack and pinion connections at 99, one at each side of the machine. The shaft 100 for idler 69 is journaled in fixed position on side bars 65 of the frame, though it may also be journaled on the carriage 64.

The transfer device T is supported and operated by members mounted on the carriage 64, including complementary levers 101 and 102 (Fig. 4), the former fixed in adjusted position upon a square rock shaft 103, and the latter upon a square rock shaft 104, both journaled in the carriage extensions 96 of the carriage ends 64x, and arranged in parallelism with the main driving shaft 95.

The lever 101 has a split socket clamp 105 mounted on its free end by means of a pivot lug 106 and through this clamp extends the shank of the sucker tube T which may be adjusted lengthwise in the clamp and then secured therein by set screws 107. By means of the lever 101 the transfer device T is moved bodily over the region of the transfer pile P toward and from the bite between the belts 36, 37. To accomplish this movement, the shaft 103 is caused to rock by the action of a disc cam 108 on shaft 95 having a peripheral track on which bears a roller 109 (Figs. 3 and 4) on an arm 110 fixed to the shaft 103 by a set screw 111. A coil spring 112 under tension biases the roller against disc 108 and tends to turn shaft 103 so as to extend the tip t of the transfer device toward the bite between conveyor belts 36, 37, as in Fig. 2. When the shoulder 113 of cam 108 turns into a position to act on roller 109 the transfer tube is retracted bodily by lever 101.

Tilting movements of the transfer tube T, producing upward and downward movement, are caused by a link 114 which connects lever 102 with an arm 115 extending from clamp 105. The shaft 104, on which lever 102 is fitted, has an arm 116, with a roller 117 biased toward a cam disc 118 on shaft 95 by a coiled spring 119 under tension. The action of this spring is to tend to depress the tip t of the transfer sucker T into the position shown in Fig. 4. When a shoulder, as 120, of cam 118 is engaged with roller 117, the arm 116 is actuated, turns shaft 104, draws link 114 and arm 115 downward, tilts clamp ear 106 on its pivot and raises tip t.

The resultant action of the two cams is a recurrent picking up and thrusting forward of the top article at any time on the clearance pile P, as will be readily understood by those skilled in the art without further elaboration of the description at this time, which is at this stage directed rather to details of structure than to mode of operation.

It is, however, desirable to note at this point that the carriage adjustment, accomplished by simply turning the hand wheel H in one direction or the other, results in shifting all of the parts mounted on the carriage without disturb-

ing their cooperative relationship. This is an outstanding feature of novelty in the present invention, and when the expression "carriage adjustment" is used, that term is employed for the sake of brevity to designate the shift not only of the carriage but of its carried mechanism.

The clearance pile has been briefly described in its general relationship to other instrumentalities so that a brief additional description of a preferred structure of the parts associated with it will be sufficient to complete the understanding of its position in the apparatus.

Referring first to Fig. 5, in which these parts are shown in plan, and to Fig. 1 in which some of them are shown schematically in elevation, it will be observed that provision is desirably made of a horizontal support, of which a part is shown at 120, taking the form of a table mounted upon a portion 121 of the frame, and over which the conveyor belt 21 (or belts, as the case may be), pulls the envelopes successively into the dash-pot position E' where their leading ends 20 respectively are engaged with the stops 33 and 33X, each succeeding envelope being pulled under the next preceding envelope as already described with reference to Fig. 1, from which the table has been omitted for the sake of clearness.

Another table part is shown in Fig. 5 at 120X, being fixed by screws 122 to suitable carriage parts. The margin 8 of the envelope blank rests upon this part of the table as it travels forward, and this part may desirably extend to a region adjacent to the inner stop 33X, so as to serve as an abutment to hold the contiguous corner of the blank up against such pressure of the sucker tip t as may be required to complete the sucking connection.

The transfer member T and its actuating and supporting mechanism are adjustable in the direction of travel of the envelope blanks to stops 33, 33X in order to operate effectively on envelopes of different lengths. This is accomplished by shifting arms 101 and 102 along shafts 103 and 104 respectively; and the table part 120 terminates at a distance from stop 33 sufficient to permit the necessary sucker adjustment, this arrangement avoiding the necessity of any adjustment of table part 120. The table part 120X may extend to stop 33X since it is not in the path of adjustment of sucker T or its supports.

A tongue and groove connection 123 (Fig. 3) between the levers 101 and 102 causes the latter to shift with the lever 101. After the sucker T has been shifted to the desired position, the levers 101 and 102 may be secured to their shafts by set screws 123a and 123b.

The part shown at 124 in Figs. 3 and 5 is an arm secured in laterally adjustable position by clamp 124a upon a cross rod 124b, and serving to support the slide 125 which carries the swinging arm 126 for roller 32, the latter being adjustable lengthwise of member 124 so as to occupy the correct position (Fig. 1) relatively to the trailing envelope end 10' adjacent to the pile P, the dimensions of which vary, of course, with different sizes of blanks.

As shown, the rollers 31 are mounted on swinging arms 131 on rod 47, being laterally adjustable thereon to compensate for different widths of blanks, and clamping means 127 are provided to secure the last-named arms in such adjusted positions.

In Fig. 4 a preferred arrangement of the upper rolls 42 is illustrated, these being shown as

mounted in pairs, each pair in a truck 128 carried by a bolt 129 on a bar 130 supported by a rod 132 depending from a bracket 133 on the cross bar 46, the latter being supported by the uprights 134. Each truck with its pair of rolls 42 is biased toward the conveyor 37, and the blanks carried thereon, by a coil spring 135 under compression.

It is to be noted that the rolls 40 nearest to the rolls 38, 39 are mounted to rotate in fixed position on the carriage upright 85, so that their position relatively to the rolls 38 and 39 is maintained.

These rolls 40 serve to insure a firm grip of the complementary conveyor belts 36, 37 upon each envelope blank E as it passes from the bite for the operation illustrated diagrammatically in Fig. 2 during travel along run R' where the gummed seal flaps 11 are folded over. The folding mechanism for this purpose is illustrated as a known form of stationary bar 140 around which the flap 11 is folded by a cam rod 140a mounted by an arm 139 (see Fig. 5) upon a suitable region of the frame, the connection not being completed, as such arrangements are a matter of convenience and well understood by those skilled in the art.

In the embodiment indicated schematically in Figs. 6 and 7 the envelope blanks are transferred from the conveyor run R', which is shown as traveling from right to left, to conveyor run R''' extending in alignment with the run R'. In this construction the blanks 10 are conveyed by belt 21' along supporting table 201 until the leading edge 210 of each blank engages one or more of the stops 33' mounted on the forward edge of table 201, and the blank is arrested and aligned thereby. In the form illustrated stops 33' are of the type suitable for arresting a blank having a straight front edge 210 of substantial extent; but it will be understood that the apparatus may be readily adapted for use with other types of envelope blank, and it may employ other types of stops well known to those skilled in the art suitable for particular types of blanks. In certain instances such stops contact the advance edges of unfolded side flaps; it is, therefore, understood that the leading edge 210 of the blank is the forward edge portion engaged by stops appropriately located for the particular type of blank.

The blanks 10 may be biased downwardly into effective engagement with belt 21' by suitable means such as presser rolls 32'. Feed belt 21' travels over idler roll 23', which advantageously may be located at a distance from stop 33' in a suitable opening in table 201, and in register with the rear portion of an envelope blank 10 engaging such stop. Leaf spring 202 mounted on bracket 203 for a presser roll 32' may be employed when desirable, especially with small blanks, and bears against the blanks 10 at a point between stops 33' and the end of effective engagement of belt 21' with blanks 10. This construction assures accurate registry and control of the blank during transfer as hereinafter indicated.

The advance portion of the uppermost blank 10 in engagement with stop 33' is shifted upwardly into position for engagement by the succeeding conveyor mechanism by means engaging the upper surface of the blank. In the form illustrated, this means comprises a sucker arm T' mounted for longitudinal adjustment in split clamp 105' fixed to rod 204 carried by the upper end of rocker levers 102', supported on pivot

shaft 205. A cam rod 206 connected to the lower end of the downward extension of one lever 102' is suitably reciprocated by a cam (not shown), and is biased by spring 207 in a direction appropriate to urge sucker arm T' downwardly into blank-engaging position.

With this arrangement the clockwise movement of rocker levers 102' about pivot 205 will lift the advance end of the uppermost blank 10 into position for engagement by conveyor sectors 84x' mounted at either side of arm T' on shaft 84' rotating in a clockwise direction. Means is provided for pressing said blank against the sectors 84x', the form illustrated including presser rolls 215 aligned with sectors 84x' and each mounted on a shaft 214 journaled in bracket 216, both brackets 216 being carried by pivot 217 on rock lever 218 supported on pivot shaft 219. Lever 218 is appropriately oscillated through cam rod 221 engaging its lower end and actuated by a suitable cam (not shown), being biased by spring 222 in a direction appropriate to maintain presser rolls 215 in retracted position as shown in full lines in Fig. 6. Each bracket 216 is provided with a tail piece 223 extending beyond pivot 217 and carrying an adjusting screw 224 bearing against the hub 225 of rock lever 218, being held yieldably in engagement with said hub by spring 226.

This construction maintains presser rolls 215 out of the path of a blank 10 during its elevation into position for engagement by sectors 84x', and then rocks rolls 215 into position beneath the blank (shown in dotted lines in Fig. 6) by appropriate movement of cam rod 221, the central stop 33' being lower than the outer stop to provide clearance for rolls 215. In this position bracket 216 extends rearwardly from pivot 217 and is biased upwardly by spring 226, providing appropriate yielding upward pressure when the blank is engaged by said sectors, the pressure of the rollers 215 being adjustable by manipulating screw 224.

A suitably driven feed roller 231 is positioned to receive the leading edge 210 of the blank 10 advanced by sectors 84x', and advantageously has a peripheral speed substantially the same as that of said sector. A presser roller 232 mounted on a forked bracket 233, located between the sectors and in registry with roller 231 serves to maintain the blanks in engagement with the latter roller. Guide rails 227 extending upwardly and forwardly from stops 33' assist in guiding the blanks between rollers 231 and 232 and thence to the bite between a central slotted feed roller 234 and an upper presser roller 42'. Rollers 234 and 42' serve to advance each blank into position on table 235 for synchronized pick-up by feed pins 228 on sprocket chains 229 extending around sprockets 230 mounted on shaft 236 which carries the feed roller 234. Sprockets 230 and chains 229 are arranged at either side of table 235 with pins 228 traveling along the sides of the table in position to engage rearward portions of blanks projecting beyond the table, such as the side flaps of the unfolded blanks illustrated in Figure 7. The pin position in this figure is illustrative and is not in proper synchronized position relative to the other parts.

The speed of rotation and relative position of the various driven blank-advancing parts, including sectors 84x', feed rollers 231 and 234, and sprockets 230 carrying chains 235 with feed pins 228, are synchronized and coordinated as to peripheral speed so that each blank picked up by sectors 84x' will be transferred into position

on table 235 in advance of the appropriate feed pins 228 at a rate sufficient to permit the retraction of presser rollers 215 and the elevation of the next blank without interference. The provision of the intermediate rollers 231 and 232 permits an earlier retraction of said rollers 215 without losing control of the blank.

In the operation of the embodiment shown in Figures 6 and 7, the blanks 10 in fanned overlapping relation are advanced by belt 21' until their forward margins 210 engage one or more of the stops 33'. When a blank reaches this position the mouth of sucker arm T' is brought down into engagement with the upper surface of the blank and is then raised by rocking the lever 102' until the blank is in alignment with the operative faces of sectors 84x' in the zone between the ends of said faces. The lever 218 is rocked to bring the rollers 215 beneath the forward end of the blank, which is picked up by the faces of sectors 84x' and advanced between the rollers 231 and 232 and thence between rollers 234 and 42' to pick-up position on table 235. The speed of these feed rollers is selected and synchronized with the operation of belt 21' and feed pins 228 to position a blank on table 235 somewhat in advance of said feed pins to assure proper synchronized pick-up by the pins. The timing is also advantageously arranged so that blank 10 is normally lifted from table 201 before the succeeding blank reaches a stop 33'; though the construction is such that the smooth continuous operation of the apparatus will not be seriously affected by an accumulation of blanks against a stop 33'; since only the uppermost blank is engaged by sucker T'. Employment of a light and flexible leaf spring 202 serves to assure the initial elevation of only the forward part of a blank 10 by sucker arm T', the blank curving about the point of engagement by the spring, which is advantageously weak enough to rise with the blank sufficiently to permit the necessary elevation of the forward part of the blank into position for engagement by sectors 84x'. This construction avoids a possible tendency to lift the succeeding blank by suction or adhesion, as might happen if the entire blank were permitted to rise with sucker T', particularly where the machine is handling very small blanks.

From the foregoing description, the operation of the machine will be clearly understood, as the sequence of steps has been explicitly set forth, and it will be sufficient to describe briefly the operations involved in effecting an illustrative adjustment in the embodiment shown in Figs. 1-5 made possible by the invention.

For example, if it be desired to operate upon a somewhat wider envelope blank, the shaft 98 will be turned clockwise (Fig. 4) by the hand wheel H (Fig. 3) to move the carriage 64 bodily to the right, carrying with it the main driving shaft 95; the shafts 67, 84, 77, 100 (when mounted on the carriage 64), 71, 103, 104, and all the parts mounted on said shafts, including the transfer sucker T, its operating levers and cams, the belt pulley rolls 38, 39 and all the gears associated with said shafts; also the idler pulleys 70 and 69. In this arrangement any slack in belts 36 is taken up by the adjustment of idler pulley 70. When, however, shaft 100 is journaled on the bars 65, slack produced by the retraction of pulley rolls 38 will be in general taken up by the retraction of idler pulleys 70, any slight change in tension being compensated by

adjustment of idler pulleys 70 by shifting arms 73 on bar 74.

I have described what I believe to be the best embodiments of my invention. I do not wish, however, to be confined to the embodiments shown but what I desire to cover by Letters Patent is set forth in the appended claims.

I claim:

1. A transfer mechanism for planiform articles of the class described, such as envelopes, said transfer mechanism comprising a run of mechanism adapted to advance a continuous band of said articles along a prescribed path to a transfer station in fanned out, overlapping relation, transfer means at a transfer station operating transversely of the direction of said path to engage each article in a zone at one side of the middle of said path and pull it in a sidewise direction relative to the direction of said path, individualizing mechanism for seizing a margin of the article which is at the opposite side of the zone engaged by the transfer means from the center of the article and for pulling the article to continue the advance initiated by the transfer means, said transfer means being timed in its operation relative to the individualizing mechanism to insure individualization of the articles.

2. A transfer mechanism for planiform articles of the class described, such as envelopes, said transfer mechanism comprising a stop located at a transfer station, a run of mechanism adapted to advance a continuous band of said articles along a prescribed path in fanned out, overlapping relation, seriatim against the stop by which registry of the leading edges of said articles is effected, transfer means at a transfer station operating transversely of the direction of said path to engage each article in a zone at one side of the middle of said path and pull it in a sidewise direction relative to the direction of said path, individualizing mechanism for seizing a margin of the article which is at the opposite side of the zone engaged by the transfer means from the center of the article and for pulling the article to continue the advance initiated by the transfer means, said transfer means being timed in its operation relative to the individualizing mechanism to insure individualization of the articles.

3. A transfer apparatus for planiform articles such as envelope blanks, said apparatus comprising a run of mechanism adapted to advance a continuous band of said articles in fanned out overlapping relation seriatim against a stop by which registering of the leading edges of said articles is effected, the uppermost article of the pile thus formed overlying progressively succeeding advancing articles; and mechanism for removing seriatim the successively topmost article of the pile so formed, said removing mechanism including cyclically operated suction pick-up means for engaging a non-central zone of the upper surface of said article and pulling it part way off the pile, and individualizing means for completing the pulling of such article from the pile during the completion of a cycle of the suction pick-up means.

4. In a machine of the class described, transfer means comprising a run of mechanism including a conveyor adapted to advance in fanned out overlapping relation a multiplicity of planiform articles each of which is foldable over at least one predetermined fold line, such as a series of envelope blanks having a foldable closure flap, said run including also means to stop said articles

successively at a given position, and in such a manner that the leading edge of each article is advanced to said stop beneath at least the next preceding article, and is maintained momentarily at least in registry with said stop, means to remove the topmost of said articles seriatim, and means to fold said foldable parts successively, said means acting in such timed relation with said advancement that each of said articles is individualized for the folding operation by the act of transfer sidewise from said overlapped relationship.

5. A transfer means for articles of the class described, comprising the mechanisms combined and cooperating as set forth in claim 1, and further characterized by having said first-named run of mechanism constituted by an elevator-conveyor belt against which said fanned out articles are biased by a superimposed series of rolls, and by a complementary run conveyor belt running at a suitable rate of speed relatively to said elevator to effect the alignment of said articles successively for said transfer.

6. An envelope making machine of the class described comprising the mechanisms combined and cooperating as set forth in claim 1, in which the individualizing mechanism comprises a pair of complementary conveyor belts disposed upon a pair of rolls spaced to receive the leading edge of said article as it is advanced by said transfer member, means to support one of said rolls with a yielding bias toward the other roll of the pair, and adjustable means to limit said biased approach of the rolls.

7. An envelope making machine of the class described comprising the mechanisms combined and cooperating as set forth in claim 1, in which the individualizing mechanism comprises a pair of complementary conveyor belts disposed upon a pair of rolls spaced to receive the leading edge of said article as it is advanced by said transfer member, means to support one of said rolls with a yielding bias toward the other rolls of the pair, and adjustable means to limit said biased approach of the rolls, and two series of complementary rolls, one adapted to support the lower belt of said pair in a right-line run, and the other series adapted to hold the upper conveyor belt toward the lower belt.

8. An envelope making machine of the class described comprising the mechanisms combined and cooperating as set forth in claim 1, in which the individualizing mechanism comprises a pair of complementary conveyor belts disposed upon a pair of rolls spaced to receive the leading edge of said article as it is advanced by said transfer member, means to support one of said rolls with a yielding bias toward the other roll of the pair, and adjustable means to limit said biased approach of the rolls, and two series of complementary rolls, one adapted to support the lower belt of said pair in a right-line run, and the other series adapted to hold the upper conveyor belt toward the lower belt, and folder means in juxtaposition to said belts and adapted to fold over a part of each of said articles, seriatim, as it is carried by said belts past said means.

9. A machine of the class described, comprising the mechanisms combined and cooperating as set forth in claim 1, and further characterized by having a frame with side members and cross members including cross shafts with rolls and conveyor belts moving in paths parallel with said side frames, and a carriage provided with a transfer device, a couple of rolls fitted with

complementary conveyor belts, and driving shafts with driving gears, all movable bodily with said carriage while preserving their cooperative relationship to permit variations in the dimensions of the blanks upon which said machine is to operate.

10. A machine of the class described, comprising a run of mechanisms adapted to advance a band of planiform articles in overlapping, fanned out relation, a guide means, and a sucker transfer member adapted to be engaged with a corner portion of each of said articles, seriatim, and means to raise said sucker member with each sheet and to shift the same in engagement with said guide, to preserve the desired alignment of said article as it is removed directly from said overlapping relationship.

11. A transfer mechanism for advancing a substantially rectangular planiform article first in the direction of its length and then in the direction of its width, said mechanism comprising a support, a stop, means for advancing the article lengthwise to said stop and means operating in a sidewise direction relative to the lengthwise advance for engaging only a single surface of the article adjacent a single corner thereof which leads both during the lengthwise and the widthwise advance, said means acting to draw said article widthwise over said support and along the stop so that said article during said transfer operation is caused by inertia and by friction to maintain its contact with said stop and be guided thereby, due to the tendency of the article to swing about the point of engagement.

12. The mechanism as set forth in claim 11 in which the means for engaging the surface of the article comprises a sucker device and means for raising and lowering the sucker device.

13. Transfer apparatus for planiform articles such as envelope blanks, comprising means for feeding a series of blanks, means for lifting the blanks in sequence from the feeding means, means for inserting a support beneath each blank in lifted position, and means engaging the upper surface of each lifted blank and cooperating with the support for advancing said blank.

14. Transfer apparatus for planiform articles such as envelope blanks, comprising means for continuously feeding a series of said articles, means for lifting the blanks individually in sequence from the feeding means, a pressure roller, means for inserting the pressure roller beneath a lifted blank, and means cooperating with the pressure roller for advancing said blank from lifted position.

15. Transfer apparatus for planiform articles such as envelope blanks, comprising stop means, means for continuously feeding a series of said articles to the stop means, means for lifting said articles in sequence after arrest by the stop means, a pressure roller, means for shifting the roller beneath a lifted article, and means cooperating with the pressure roller for advancing the articles from lifted position.

16. Transfer apparatus for planiform articles such as envelope blanks, comprising stop means, means for feeding an article against the stop means, article conveying means, means for upwardly shifting an article arrested by the stop means into engagement with the conveying means, said shifting means engaging the forward part of the article adjacent the stop means, and upwardly yieldable pressure means engaging said article during shifting at a point spaced rearwardly from the point of engagement of the shifting means with said article.

17. Transfer apparatus for planiform articles such as envelope blanks, comprising means for continuously feeding a series of said articles, stop means for arresting said articles in sequence, means for lifting said articles in sequence after arrest by the stop means, a feed sector engaging the upper surface of each lifted article, and a presser roller engaging the lower surface of the lifted article in register with the feed sector, said roller and sector being arranged and operated to advance the articles in sequence.

18. Transfer apparatus for planiform articles such as envelope blanks, comprising means for feeding a plurality of said articles in series, stop means for arresting the articles in sequence, means for engaging and shifting a segment of each successive article upwardly from arrested position at the stop means, and means for engaging and pulling each upwardly shifted segment to remove the article from arrested position, including a feed unit comprising an upper feed member and a cooperating lower feed member, the lower feed member being movable into and out of operative position to permit the upward movement of the article.

19. Transfer apparatus for planiform articles such as envelope blanks, comprising means for feeding a plurality of said articles in series, stop means for arresting the articles in sequence, means for engaging and shifting a segment of each successive article upwardly in sequence from arrested position at the stop means, and means for engaging and pulling each upwardly shifted segment to remove the article from arrested position, including a feed unit comprising an upper feed member and a cooperating lower feed member, the lower feed member being movable into and out of operative position to permit the upward movement of the article, and a second feed unit engaging and forwarding each article while still engaged by the first feed unit.

20. In a sheet feeding and forwarding mechanism, a feed table, means for delivering a series of envelope blanks in spaced relation to each other to said feed table, means associated with said feed table for arresting the forward movement of said blanks and thereby accumulating a plurality of said blanks in aligned position at said arresting point, and means for continuing the advance of each blank to alining and folding mechanisms of the machine.

21. In a machine of the kind described, in combination, sheet feeding means for advancing a succession of sheets in band formation with each sheet underlapping its predecessor of the band, stop means standing in obstructing relation to the advancing sheets for arresting them one after another at a rest station, cyclically operated suction means acting periodically to engage and lift a non-central zone of an arrested sheet at said station, and individualizing means for seizing a marginal area of the sheet adjacent the zone engaged by the suction means to pull the sheet away from the rest station and to feed it completely clear of the rest station during the completion of a single cycle of the suction means.

22. In a machine of the kind described, in combination, sheet feeding means for advancing with predetermined, substantially uniform frequency a succession of sheets in band formation with each sheet underlapping its predecessor of the

band, stop means standing in obstructing relation to the advancing sheets for arresting them one after another at a rest station, cyclically operated suction means acting periodically and with a frequency corresponding to the frequency of the arrival of the sheets at said station to engage and lift a non-central zone of an arrested sheet at said station, and individualizing means for seizing a marginal area of the sheet adjacent said zone which is engaged and lifted by the suction means to pull the sheet away from the rest station and to feed it completely clear of the rest station during the completion of a single cycle of the suction means.

23. An individualizing transfer mechanism for planiform articles comprising, in combination, a run of mechanism for advancing a continuous underlapped band of such articles seriatim to a transfer position, a lifter for operating on the articles seriatim, means operating the lifter periodically to cause it to engage each article in a non-central zone thereof and to pull the article away from the transfer position by the engaged zone thereof with the center of the article trailing the engaged zone, and individualizing mechanism for seizing a margin of the article which is at the opposite side of the zone of lifter engagement from the center of the article and for pulling the article to continue the advance initiated by the lifter and move the article clear of the next following article, said lifter operating means being timed in its operation relative to the individualizing mechanism to insure individualization of the articles.

24. An individualizing transfer mechanism for planiform articles comprising, in combination, a run of mechanism for advancing a continuous underlapped band of such articles seriatim to a transfer position, a lifter for operating on the articles seriatim, means operating the lifter periodically to engage each article in a non-central zone thereof and to lift a portion at least of said article, and individualizing mechanism for seizing a margin of the lifted article which is at the opposite side of the zone of lifter engagement from the center of the article and for pulling the article clear of the next following article, said lifter operating means being timed in its operation relative to the individualizing mechanism to insure individualization of the articles.

25. An individualizing transfer mechanism for planiform articles comprising, in combination, a run of mechanism for advancing a continuous lapped band of such articles seriatim to a transfer position, a sucker for operating on the articles seriatim, means operating the sucker periodically to cause it to engage each article in a non-central zone thereof and to displace a portion at least of such article out of the plane occupied by it in the transfer position, and individualizing mechanism for seizing a margin of the article which is at the same side of the center of the article as the zone of sucker engagement, and which has been displaced by the sucker, to move the article clear of the next following article, said sucker operating means being timed in its operation relative to the individualizing mechanism to insure individualization of the articles.

ABRAHAM NOVICK.
